MEANS FOR INDICATING AND SYNCHRONIZING THE VELOCITIES OF TWO ELEMENTS.

Application filed June 26, 1926. Serial No. 118,652.

This invention relates to means for automatically indicating differentials between, and synchronizing or controlling the velocities of two elements or surfaces.

The principal objects of the invention are to provide means for automatically indicating differential between and synchronizing the relative velocities of two relatively moving elements or surfaces; also to provide means adapted to be actuated by the movement of said elements, and which, when differentials occur between the velocities of said elements, is adapted to automatically effect the synchronization of the velocities of said elements; also to provide synchronizing means adapted to actuate a signal for indicating normal and abnormal conditions relative to the moving elements; also to provide synchronizing means for the purpose stated which is adapted to be actuated by the movement of said elements with the minimum of power, and to provide relay or speed control means adapted to be actuated by said synchronizing means to control and synchronize the velocities of said moving elements, as by the actuation of a variable speed mechanism or device.

Other objects of the invention are to provide indicating or synchronizing or controlling means of the character described for use on paper making machines, for indicating and synchronizing and controlling the relative velocities of two members thereof; and also to improve means of this sort in the other respects hereinafter specified and claimed.

In the drawings:

Fig. 1 is a diagrammatic illustration of the "wet end" of a Harper paper making machine, having applied thereto one form of automatic differential indicating and speed synchronizing mechanism, embodying the present invention, for indicating and synchronizing or controlling the velocities of the wire screen and felt thereof.

Fig. 2 is a diagrammatic view showing the wiring and connections for the illuminated signal, which is actuated by the synchronizing mechanism, and is employed for apprising the operative of conditions of the machine.

Fig. 3 is a diagrammatic view, on an enlarged scale, of the driving end of the ma-

chine disclosed in Fig. 1, showing the differential indicating and synchronizing or speed controlling mechanism in operative relation thereto.

Fig. 17 is a diagrammatic illustration of the signalling means adapted to be actuated by the synchronizing mechanism shown in Fig. 11.

Fig. 18 is a side elevation, partly in section, of the form of relay or speed controlling mechanism for effecting the control of the variable speed mechanism of the machine shown in Figs. 10 and 16.

Fig. 19 is a transverse, sectional view thereof on line 19—19, Fig. 18.

In paper making machines, for example, of the Harper type, a traveling wire screen is used to carry a layer of pulp stock into a position where an endless traveling "felt" 5 or apron is pressed against the screen so that the layer of stock is imposed upon the felt, to be carried thence to the press rolls and driers. It is necessary that the velocities of the screen and felt be identical so that the 10 layer of paper is transferred from one member to the other without strain or other undesirable condition affecting the strength and quality of the paper. While the felt is usually driven directly from a prime mover, 15 the wire screen is driven through a variable speed device, such as a cone pulley and belt having a shifter device.

Differentials in the intended speeds of the screen and felt occur, due to various well 20 known reasons, and it has been the practice to attempt to eliminate these, and synchronize, as far as possible, the velocities of the two elements by manually actuating the shifter of the cone pulley belt to change the 25 speed of the wire screen.

Such methods, however, are only approximate, and depend largely upon the individual judgment of the operative, and in any event, the undesirable conditions remain 30 until his attention is called, in some manner, to the presence of such conditions, as by a difference in sound of the moving parts, by an examination of the product from the machine, or otherwise.

35 In the present application, the term "synchronize" is intended to cover the control of the velocities of the two elements, not only when these are alike, but also when the velocities are of any desired or predetermined ratio.

Briefly described, the automatic velocity indicating and synchronizing means of this invention comprises a differential mechanism, such as any well known type of gear 45 differential, having its two rotatable members or shafts operatively connected with parts engaging the elements to be synchronized and movable thereby at the same velocity as the respective elements. As long 50 as there is no variation in the velocities of the two elements, no differential action occurs in said mechanism, but when such variations occur, then the differential movement resulting in said mechanism is made use 55 of to actuate, either directly or indirectly, (preferably the latter for practical reasons) the variable speed device or other means used to drive and change the speed of one of said moving elements, so as to change the 60 velocity thereof and synchronize it with that of said other element. In practice, we prefer to employ, between the differential mechanism and the variable speed mechanism, means adapted to be actuated by the 65 rotation of the planetary gear element of the

differential mechanism, and which in turn actuates the variable speed mechanism, to effect such synchronization.

The invention is applicable widely to many different situations where it is desirable to synchronize the velocities of two moving elements, whether these are in contact or not, and will effect such synchronization whether they are both intended to operate at the same speed, or in any speed ratio one to the other.

In the present application, the invention is disclosed in use on paper making machinery, two variations being shown, one in connection with a Harper type of machine for automatically indicating and synchronizing the velocities of the endless wire screen and felt apron thereof, and the other in connection with a cylinder type of paper making machine for synchronizing the peripheral velocity of the rotary wire screen with that of the endless felt. It is to be understood, however, that either form may be used with each type of machine, and also that the invention may be employed to indicate differentials in and synchronize the velocities of any two other traveling or rotating parts or units of paper machines of the types mentioned, or of other types, and of the parts or units of many other machines or apparatus, either mechanical, hydraulic or electrical, or combinations thereof. Furthermore, the particular construction of the differential mechanism and the means actuated thereby to control the variable speed mechanism may be varied to suit conditions met with, as will be apparent from the subject matter to follow.

The Harper paper machine, Figs. 1, 3 and 4, includes, as usual, an endless wire screen or apron 10 upon the upper run of which the pulp, in suspension, is deposited and is carried in the direction of the arrow, while most of the water drains away through the meshes of the screen. The screen 10 passes downwardly over, and is driven by, a couch roll 11, and then travels rearwardly over idler guide rolls 12. Another idler guide roll 12 is also positioned beneath the upper run of the screen adjacent the couch roll 11. The couch roll 11 is driven by a variable speed mechanism, comprising a cone pulley 13 fixed on a shaft 14 having a pinion 15 meshing with a gear 16, secured, in turn, on a shaft 17 on which the couch roll 11 is fixed. The cone 13 is rotated by a belt 18 passing over a pulley 19, rotated by a pulley 20 on the same shaft, and belt 21, through the medium of a pulley 22 on a line shaft 23. An endless apron 23, or "felt" is pressed against the screen 10 as it passes over the roll 11, to pick up and remove the layer of pulp therefrom by a loosely mounted couch roll 26, beneath which it passes in the same direction as the wire

screen, and thence travels forwardly over a "turning" roll 27, and then upwardly and rearwardly over idler guide rolls 28 to and between a pair of rolls 29 of the press, where the paper web leaves the felt and passes through the press and drier sections of the machine. The lower run of the felt is guided to the front of the machine over a plurality of idler rolls 30. The felt 25 receives its movement from, and its velocity is substantially equivalent to, that of the press roll 29 over which it passes, and this roll receives its rotation from a pulley 32, connected by a belt 33 to a pulley 34 on the line shaft 23. The felt 25, therefore, is directly driven at a substantially predetermined speed, while the wire screen 10 is adapted to be driven through the variable speed device, as described.

In accordance with the previous practice, the velocity of the screen 10 has been regulated by manually shifting the belt 18 lengthwise of the cone pulley, so as to drive said pulley, and through it and the gears described, the couch roll 11 at the same velocity as the felt 30, as nearly as could be ascertained, and when obvious variations or differentials in velocities between these two members occurred, for any reason, the position of the belt 18 on the cone pulley 13 has been changed.

The belt shifting means comprises the usual screw shaft 36, and belt shifter or yoke 35 transversely movable on said shaft, which is prevented from endwise movement and is turned by a hand wheel 37.

In the present instance, therefore, the wire screen 10, and the felt 25 are the two elements, the velocities of which it is desired to automatically indicate and synchronize or control, through the means of this invention.

The differential mechanism shown in Figs. 3, 4 and 15, is of a well known form comprising a casing 40 having therein a pair of opposed bevel gears 41, 42 attached respectively to aligned shafts 43, 44, one of which preferably extends through the other and is rotatable therein. The shafts 43, 44 are journaled in bearings 45, and an end of each shaft extends outwardly through the casing, for the attachment thereto of pulleys 46, 47, respectively.

Loosely journaled about the inner end of the shaft 43 for rotation thereon is a fork 50 in the outer, opposite ends of which are journaled stub shafts 51 each carrying a bevelled pinion 52. The shafts 51 are arranged in alignment at diametrically opposite sides of the axis of the shafts 43 and 44 and perpendicular thereto and are adapted to support their pinions in mesh with both of the bevelled pinions 41 and 42. As long as the pulleys 46 and 47 turn at the same speed, the two pinions 41 and 42 will likewise turn at

the same speed, and the pinions 52 will turn idly therewith, but should a differential occur in the velocities of said pulleys, the fork or member 50 will be rotated about the axis of the shafts 43 and 44 in one direction or another. The direction in which this movement occurs is preferably indicated by means of a pointer 53 secured outside of the case 40 to the extended hub 54 of the fork 50.

The pulleys 46 and 47 are adapted to be rotated by the travel of the felt 25 and screen 10 respectively, and at the same velocities, to drive the differential mechanism, this being accomplished in any suitable manner. In the arrangement shown in Figs. 1, 3 and 4, freely rotatable parts over which the elements 10 and 25 pass, such as one of the idler rolls 12 and one of the idler rolls 30, respectively, are utilized for this purpose, the movement of the roll 12, for example, being transferred to the pulley 47 by a crossed belt 56 passing thereover and over a pulley 57 secured to the shaft of the roll 12. Likewise, the idler roll 30 has secured to its shaft a pulley 58 of the same diameter as the roll, this pulley being connected to the other pulley 46 of the differential by a belt 59. For convenience, the rolls 12 and 30 and their respective pulleys 57 and 58, and the differential pulleys 46 and 47 are all made of the same diameter, so that the pulleys 46 and 47 are rotated at the same velocities as the felt 25 and screen 10 respectively, through the connections described.

It will be seen from the foregoing that when the velocity of the screen 10, for example, varies from that of the felt 25, a rotation of the fork 50 occurs, and this rotative movement is utilized in any suitable manner for the purpose of turning the screw shaft 36 of the shifter mechanism in one direction or the other, so as to shift the belt 18 longitudinally of the cone pulley 13 to effect the necessary change in speed of the couch roll 11, through the described connections, to correct or eliminate the variation in speed between the elements and automatically synchronize the velocities thereof.

It is undesirable, however, in practice, to place any substantial load on the pulleys 57 and 58 of the idler rolls 12 and 30, as otherwise slipping would occur between these rolls and the elements 10 and 25 which turn them, thus destroying the accuracy of the differential indicated by the differential mechanism. However, the casing 40 of the differential mechanism is preferably filled with lubricant and very little power is required to turn the pulleys 46 and 47 thereof or to effect the differential movement of the member 50. Therefore, means of suitable sort, in the nature of a relay, is interposed between said member 50 and the shifter

mechanism for the belt 18 for the purpose of increasing the power which results from the rotative movement of said member 50 and translating this movement into the linear movement necessary to effect the shifting of said belt 18.

The relay or controlling means for this purpose can be of any suitable construction or type, for example, the rotation of the member 50 could be used to actuate switches, to control a reversible electric motor suitably connected to the screw shaft 36 to turn the same in one direction or another, or, if desired, either a mechanical device or a hydraulic mechanism may be used.

In order to illustrate this phase of the invention, a suitable mechanical device is shown in connection with the Harper paper making machine shown in Figs. 1, 3 and 4, and is illustrated in detail in Figs. 5 to 9, while a hydraulic mechanism is shown in connection with the cylinder machine of Figs. 10 and 16, this mechanism being illustrated in detail in Figs. 12, 18 and 19.

The mechanical relay or control device shown in Figs. 3 to 9, and employed for the purpose set forth, is constructed as follows:

Rigidly secured on the shifter screw shaft 36 adjacent one end thereof, are two ratchet wheels 65 and 66, disposed between a pair of supporting brackets 67 for supporting that end of the shaft, the other end thereof being journalled, so as to prevent endwise movement of the shaft, in a bracket 68. Dogs or detents 69 and 70 are provided for the ratchets 65 and 66 respectively. These dogs extend horizontally in the plane of the ratchets, and are each pivoted at one end to the upper end of a lever 71 at one side of the screw shaft, while the free ends thereof are supported at the opposite side of the screw shaft on rollers or the link 72. Each dog is provided, between its ends, with a detent tooth for engagement with the teeth of the corresponding ratchet. The lower ends of the levers 71 are pivoted to a fixed lug, and they are both connected by means of a rod 73 to an eccentric strap 74 surrounding an eccentric 75 fixed on a shaft 76 extending parallel with the screw shaft at one side thereof. This shaft 76 is provided with a pulley 77 which is rotated from any suitable adjacent part of the machine for actuating the eccentric, for example, by means of a belt 78, Figs. 3 and 4, and a small pulley 79 on the shaft 14 of the cone pulley 13. The supporting rollers 72 for the dogs 69 and 70 are each journalled in a fork at the upper end of a vertical rod 80. Each rod slidably extends through guide sleeves 81 of fixed brackets 82 and the lower end of each rod is pivoted to an end of a rocker 83, rigidly secured on a horizontal rock shaft 84 journalled in fixed bearings 85.

The shaft 84 is adapted to be turned, in any suitable way, by the rotatable member 50 of the differential, as by a coupling 86 connecting it to one end of a flexible shaft 87 and the other end of which is secured to the outer end 54 of said rotatable fork or member 50. As long as there is no differential movement indicated in the differential, and consequently no rotation of the member 50, the dogs 69 and 70 will be in the position shown in Fig. 7, that is, with their respective teeth or detents disengaged from their respective ratchet wheels, for at this time the rocker 83 will be horizontal and the rollers 72 will both be at the same elevation. Consequently, the reciprocation of the dogs through the eccentric 75, and the oscillation of the levers 71 will have no effect on the ratchets, and the screw shaft 36 will remain stationary. Thus, the ratchet control device will be inert and the position of the shifter yoke 35 will not be changed. However, as soon as differential occurs, causing rotative movement of the member 50, the flexible shaft 87 will turn the rock shaft 84 and rocker 83 in one direction or another, elevating one of the rollers 72 to a position in which it will hold its dog entirely out of contact with the corresponding ratchet wheel, at the same time lowering the other roller 72, and allow its dog to engage its ratchet.

The rotation of the eccentric 75 will now cause the dog, which remains in contact with the corresponding ratchet, to move this ratchet step by step in one direction and effect an intermittent rotation of the screw shaft in that direction. Thus the shifter fork 35 will travel lengthwise of the screw in a direction to shift the belt 18 on the cone 13 so as to either increase or decrease the speed of the couch roll 11 as the case may be, in order to synchronize the velocity of the wire screen or element 10 driven thereby with that of the felt 25. When the necessary change in speed has been effected, and the two elements have been synchronized, the differential movement of the member 50 will gradually decrease and finally cease, and the two pulleys 46 and 47 will then rotate their respective shafts at the same speed, thus permitting the rocker 83 to again assume its normal horizontal position, and allow both dogs 69 and 70 to disengage from their respective ratchets, as before.

From the foregoing, it will be observed that the velocity of the element 10 is referred to or synchronized with that of the element 25, the speed of which is substantially constant, being driven, as described, through direct driving connections, while the element 10 is driven through a variable speed mechanism. In this particular arrangement, as before stated, the requirement is to synchronize the velocities of the two

elements for the purpose of producing a uniform product. However, should the velocity of the felt or element 25 fluctuate from any cause, the indicating and synchronizing means described will nevertheless automatically operate to change the velocity of the wire screen 10 or element 10 to synchronize it with the change in the velocity of the element 25, thus maintaining the correct conditions for the production of uniform paper.

The cylinder type of paper making machine shown in Figs. 10 and 16 is of well known construction, having a felt or other element 90 in the form of an endless apron which passes between and is driven by a pair of press rolls 91 and is guided by a plurality of idler guide rolls 92. The forward end of the felt 90 passes beneath a floating couch roll 93 and over a turning roll 94. The couch roll 93 is adapted to press the felt 90 into contact with a rotary screen or cylinder 95, the periphery of which is covered with wire mesh and which rotates in a vat 96, as usual, to pick up the pulp held in suspension in the vat and transfer it to said felt 90.

The rotary screen or drum 95 constitutes the other element equivalent to the wire screen 10 of the previous construction, and the velocity of which it is desired to automatically synchronize with that of the felt 90.

The cylinder 95 is driven through a variable speed transmission mechanism interposed between its shaft 97 and the extended shaft 98 of one of the press rolls 91, which in turn receives its power from the bevel gear 99 and pinion 100. A cone pulley 101 has its shaft operatively connected to the shaft 98 by sprocket and chain 102, and a belt 103 passing over said cone 101 also passes over another cone pulley 104 having on its shaft 105 a pinion 106 meshing with a gear 107 secured on the shaft 97 of the cylinder 95. The shifter screw shaft 108 is rotatably mounted and secured from endwise movement at one side of the pulley 104 and is provided with a shifter yoke 109, embracing the belt 103 for shifting the same on the cone 104. The described drive connections are such that when the belt 103 is approximately midway between the ends of the cones 101, 104, the velocity of the cylinder 95 is substantially the same as that of the felt 90.

The slightly modified differential mechanism used in connection with this cylinder machine is shown at 112, Figs. 10 and 16, and the relay or controlling means interposed between said mechanism and the variable speed mechanism is indicated at 113. This device 113 is in the form of a hydraulic engine or motor for automatically changing velocity and direction of rotation of the cone 35 of the variable speed mechanism as indi-

cated by the synchronizing mechanism. This mechanism 113 comprises a casing 114 in which is arranged a pair of sylphon bellows 115, 116 or other members adapted to expand upon the introduction of a fluid 70 thereinto, such as water, conveyed thereto by means of pipes 117, 118, respectively, connected thereto and extending out of said casing 114. The diaphragm 120 of each bellows is connected to a plunger rod 121 extending downwardly therefrom. The diaphragm 120 and rod 121 are normally held in the upper position shown in Figs. 18 and 19, by a coil spring 122 bearing against the diaphragm and against a collar 123 loosely 80 surrounding the plunger and engaging a transverse fixed part 124 through which the rod 121 extends. The lower ends of the two rods 121 are pivotally connected to horizontal yokes or forks 126, 127, respectively. The inner ends of both forks are pivoted or hinged on a transverse shaft 128 journaled in the casing 114 and having one of its ends 90 extending therethrough and provided with a pulley 129. Secured on the shaft 128 between the forks is a pinion 130 meshing with a similar pinion 131 on a transverse shaft 132 journaled in the yoke 126, and on which is rigidly secured a roller 133. A similar shaft 134 is journaled in the other yoke 127. This shaft is also provided with a roller 135 and pinion 136, the latter meshing in turn with an idler pinion 137 which engages and is rotated by the pinion 130 on the shaft 128. It will be seen that the rotation of the shaft 130 will drive the rolls 133 and 135 in opposite directions. Disposed beneath the rollers 133 and 135, and in spaced relation thereto, is a large roll 140 secured on a transverse shaft 141 journaled in the casing and having a pinion 142 meshing with a gear 143 on another transverse shaft 144 which, in turn, is provided with a pinion 145 meshing with a gear 146 on still another shaft 147, one end of which extends through the casing and has secured thereon a sprocket wheel 148. This sprocket wheel is connected by means of a sprocket chain 149 to another sprocket wheel 150 secured to one end of the shifter screw shaft 108. The pulley 129 on the shaft 128 is connected by means of a belt 151 to a pulley 152 secured to the shaft 105 of the cone pulley 104. The shaft 128 and the two rollers 133, 135 are constantly driven from the shaft 105 through the described connections, but in normal operation, or as long as there is no differential between the cylinder 95 and the felt 90, the two rollers 133, 135 remain out of contact with the roller 140, as shown in Fig. 18. However, should differential occur, the differential mechanism will operate, as about to be described, to cause the introduction of fluid into one or the other of the sylphon bellows 115 or 116, depressing the 130

diaphragm and plunger thereof and rocking the yoke connected thereto about the shaft 128, thus moving one of the rollers 133 or 135 into contact with the roller 140. The roller 140 will thus be rotated in one direction or the other by friction, and through the described gear train and sprocket connections, cause a rotation of the shifter screw 108 to move the belt lengthwise in one direction or another along the cone 104 in the proper direction to effect the synchronization of the velocity of the cylinder 95 with that of the felt 90.

The differential mechanism 112 is of somewhat different form to that shown in Figs. 3, 4 and 15, but is of a similar type. This mechanism, see Figs. 11, 13 and 14, includes a casing 155 in which is journaled two axially aligned stub shafts 156, 157. These extend through bearings in the casing and are provided on their inner ends with pinions 158, 159 respectively. The outer end of the shaft 156 has secured thereto a pulley 160, and the corresponding end of the shaft 157 has secured thereto a pulley 161. A rotatable ring or member 162 embraces, and is journaled on the hubs of the pinions 158, 159, and is provided with diametrically opposed pinions 163, 164 meshing with both pinions 158, 159. The rotary ring or member 162, has an annular groove or track 165 in which are disposed a pair of arcuate friction shoes 166 having their lower ends pivoted or hinged together at 167, while their opposite ends are provided with lugs 168 spaced apart. A rod 169 extends through the lugs and has a head between which and one of the lugs is an expansion spring 170 for frictionally holding the shoes 171 against the bottom of the groove 165. The two lugs 168 and 169 extend at opposite sides of and in spaced relation to a finger 171 fixed on a transverse rod 172, the ends of which extend through holes at opposite sides of the casing. The rod is provided with stop pins 173 between which and the side walls of the casing expansion springs 174 are arranged to yieldingly hold the finger 171 midway between the lugs 168 and 169, as shown in Figs. 11 and 13. One end of the rod 172 is operatively connected to an ordinary four-way hydraulic pilot valve 172^a of well known construction provided with an inlet pipe 175 and an outlet pipe 176 for the entrance and exit of water or other fluid. The valve is provided with two ports connecting respectively with the pipes 117 and 118 leading to the siphon valves 115, 116, and is normally held in position to close the ports for said pipes 117 and 118 by the rod 172 through the springs 174.

The pulley 160 of the differential mechanism is, as in the previous construction, operatively connected, in any suitable man-

ner, to a freely rotatable part of the machine 63 engaging with and moving at the same velocity as one of the elements to be synchronized, in this case, the idler roll 92 over which the felt 90 passes. The extended shaft 180 of this roll is provided with a pulley 181, connected by a belt 182 to said pulley 160, said roll 92, pulleys 181 and 160, being all of the same diameter, so that the pulley 160 travels at the same velocity as the element 90. The other pulley 161 of the differential mechanism is likewise connected by a belt 183 to a pulley 184 on the end of the shaft 105 of the cone pulley 104 or a pulley on shaft 97 having the same diameter as the cylinder 95. The pulleys 161 and 184 are of like diameter and the diameter of the pulley 184 is such that, through its gear connections with the shaft 97, it is adapted to have the same peripheral velocity as that of the rotary screen or element 95.

When no differential occurs between the velocities of the two elements 90 and 95, there will be no differential movement of the ring 162, and the friction shoes 166 will remain substantially stationary, thus allowing the rod 172 to maintain its central position shown in Fig. 11, so that the hydraulic valve will be in a position to close the ports leading to the pipe 117 and 118. Therefore, there will be no actuation of the siphon bellows for the fluid entering the pipe 175 will pass directly through the valve, and out of the outlet pipe 175. When, however, differential occurs in the velocity of the two elements 90, 95, the differential ring 162 will rotate and carry the shoes 166 therewith in frictional contact in one direction or another until one of the lugs 168 engages and shifts the finger 171, rod 172 and valve 173 in one direction or the other to permit fluid to enter one of the pipes 117 or 118, thus actuating one of the siphon bellows and engaging the corresponding roller 133 or 135 with the roller 140. When this occurs, the roller 140, through the described gear and sprocket connections, will rotate the shifter screw 108 to move the shifter yoke 109 in the proper direction to shift the belt 103 and change the speed of the cone pulley 104, thus synchronizing the velocity of the cylinder 95 with that of the felt 90. When this synchronization has been effected, the various parts of the differential mechanism 112 and the relay or control mechanism 113 will again assume their normal positions, and the rotation of the screw 108 will cease.

The described constructions of the differential mechanism and of the controlling or relay mechanisms are intended only as illustrative of the invention, and we wish it to be understood that we do not limit ourselves to these disclosures, as other suitable mech-

anisms may be substituted therefor without departing from the spirit and scope of our invention.

It is desirable to provide means whereby the person attending at the machine may be apprised of the presence of abnormal conditions affecting the two elements which are to be synchronized, such as some sort of visible or audible signal. In the drawings, an electrical system is included having therein a series of lamps, for example, a white light constantly burning to indicate that the system is in order, a blue lamp which may be arranged to light when the velocity of the element driven by the variable speed mechanism is operating at lower than normal speed, and a red lamp adapted to light when the velocity of said element is above normal, this increased velocity usually occurring through conditions which, if left uncorrected, might cause injury to the machine.

In Fig. 2 is shown such a system adapted for use with the indicating and synchronizing means shown in Figs. 3, 4 and 15, and which comprises a switch box 180 having a contact arm 181 pivoted therein and which is provided with a contact member 183 adapted to occupy, when there is no differential movement, an intermediate position between two fixed contacts 184 and 185 connected respectively by conductors 186, 187 to blue and red lamps 188 and 189. These lamps are further connected by conductors 190, 191 to one conductor 192 of the feed line. The white light 193 is directly connected to said conductor 192 and to the other conductor 194 of the feed line to burn continuously. A second contact 195 on the contact arm 181 is connected to the line 194 by a conductor 196. It will be seen from the diagram that if the arm 181 is swung into contact with either of the contacts 184, 185, the circuit to the lamp 188 or the lamp 189, as the case may be, will be closed.

The arm 181 is adapted to be actuated for this purpose in any suitable manner, when differentials occur in the velocities of the two elements 10 and 25, this being accomplished by providing an arm 198 fixed to the extended hub 54 of the rotary differential member 50, said arm 198 having its outer end connected by a link 199 to the outer end of the contact arm 181, so as to move the same when rotary motion is imparted to the member 50.

A slightly modified form of electrical signal means is shown in Figs. 11, 13 and 17. In this case, a white light 200, burning constantly, as before, is provided, and colored lights 201, 202 are used in the same manner and for a similar purpose to that just described.

The contacts for these lamps, however, are associated with the differential mechanism

112, so as to be operated directly thereby. For this purpose, the end of the reciprocating valve operating rod 172, which is remote from said valve 172, extends into a switch box 203 secured on the casing 155, said rod end being provided with a fixed block having a contact member 204 secured thereon. This contact is adapted to move with the rod and engage either a contact 205 or a contact 206 secured respectively on arms 207, 207a pivoted at 208 and which are adapted to be held, by means of a spring 209 connecting both arms, yieldingly against a stop plate 210 in such position that when no differential occurs, the contact 204 is intermediate of, and out of engagement with, the contacts 205 and 206. These last mentioned contacts are respectively connected by conductors 212, 213, contact members 214, 215, conductors 216, 217, to one terminal, respectively, of each of the lamps 201, 202. The other terminals of these lamps are connected by branches 219, 220, conductor 221, contacts 222, 223, to one side 224 of the feed line. The other conductor 225 of the feed line is connected through contacts 226 and conductor 227 to the contact 204 and a conductor 228 connected at 226 to the feed 225, leads through contacts 230 and conductor 231 to one terminal of the white light 200, the other terminal of this light being connected to the branch 219 before mentioned. The various contacts 214, 223, 226 and 230 are arranged on an insulated plate 232 of which the stop plate 210, before mentioned, forms a part. By this arrangement, differential movements occurring in the mechanism 112 and causing an endwise movement of the rod 172 will shift the contact member 204 into engagement with either the contact 205 or 206 to light one or the other of the lamps 201, 202 through the described connections. Obviously, any other suitable circuit may be employed to light lamps in the manner described, or, if desired, the lamps could be replaced by bells or other audible signals, or the signal means can be dispensed with, if desired.

We claim as our invention:

1. Means for automatically synchronizing the velocities of two movable carrier elements each having a surface portion in close proximity to the other and moving in the same linear direction, said means including two rotatable members one of which operatively engages each of said carrier elements so as to be rotated through the movement thereof and at least one of said members being freely rotatable and frictionally engaging one of said carrier elements so as to be rotated thereby at a peripheral speed corresponding to the velocity of said element, a differential mechanism operatively associated with and driven by said rotatable members, said differential mechanism hav-

ing a differential member which moves as the speeds of said rotatable members vary when differentials occur between the velocities of said carrier elements, and means adapted to be actuated by the movement of said differential member to automatically change the velocity of one of said carrier elements and synchronize the same with that of said other carrier element.

10 2. Means for automatically synchronizing the velocities of two movable carrier elements each having a surface portion in close proximity to the other and moving in the same linear direction, one of said carrier elements being driven through a variable speed mechanism, said automatic synchronizing means including two rotatable members one of which operatively engages each of said carrier elements so as to be rotated through the movement thereof and at least one of said members being freely rotatable and frictionally engaging one of said carrier elements so as to be rotated thereby at a peripheral speed corresponding to the velocity of said carrier element, a differential mechanism operatively associated with and driven by said rotatable members, said differential mechanism having a differential member which moves as the speeds of said rotatable members vary when differentials occur between the velocities of said carrier elements, and means adapted to be actuated by the movement of said differential member to actuate said variable speed mechanism to automatically effect a change in the velocity of the carrier element driven therethrough and synchronize it with that of said other carrier element.

40 3. Means for automatically synchronizing the velocities of two movable carrier elements each having a surface portion in close proximity to the other and moving in the same linear direction, one of said carrier elements being driven through a variable speed mechanism, said automatic synchronizing means including two rotatable members one of which operatively engages each of said carrier elements so as to be rotated through the movement thereof and at least one of said members being freely rotatable and frictionally engaging one of said carrier elements so as to be rotated thereby at a peripheral speed corresponding to the velocity of said carrier element, a differential mechanism operatively associated with and driven by said rotatable members, said differential mechanism having a differential member which rotates as the speed of said rotatable members vary when differentials occur between the velocities of said carrier elements, whereby the rotation of said differential member is utilized to actuate said variable speed mechanism and effect a change in the velocity of said carrier ele-

ments driven therethrough and synchronize it with that of said other carrier element.

4. Means for automatically synchronizing the velocities of two movable carrier elements each having a surface portion in close proximity to the other and moving in the same linear direction, said means including two freely rotatable cylindrical members one of which is disposed so that its periphery frictionally engages each of said carrier elements so as to be rotated through the movement thereof at a peripheral speed corresponding to the velocity of said carrier element, a differential mechanism, said mechanism having two members operatively associated with and driven by said freely rotatable members, and a rotatable differential member which is revolved by said rotatable members as the relative speeds thereof vary when differential occurs between the velocities of said carrier elements, and means whereby the rotation of said differential member is utilized to effect a change in, and synchronize the velocity of one of said carrier elements relatively to that of said other carrier element.

5. Means for automatically synchronizing the velocities of two movable carrier elements each having a surface portion in close proximity to the other and moving in the same linear direction, said means comprising two freely rotatable cylindrical members one of which is disposed so that its periphery frictionally engages each of said carrier elements so as to be rotated through the movement thereof at a peripheral speed corresponding to the velocity of said carrier element, a differential mechanism, said mechanism having two members operatively associated with and driven by said freely rotatable members, and a rotatable differential member which is revolved by said rotatable members as the relative speeds thereof vary when differential occurs between the velocities of said carrier elements, a variable speed mechanism through which one of said carrier elements is driven, said rotatable differential member being operatively connected to said variable speed mechanism to effect a change in the velocity of the carrier element driven therethrough, and synchronize it with that of said other element irrespective of variations in velocity of said last carrier element.

6. Means for automatically synchronizing the velocities of two movable carrier elements each having a surface portion in close proximity to the other and moving in the same linear direction, said means comprising two freely rotatable cylindrical members one of which is disposed so that its periphery frictionally engages each of said carrier elements so as to be rotated through the movement thereof at a peripheral speed corre-

- sponding to the velocity of said carrier element, a differential mechanism operatively associated with and driven by said rotatable members, said differential mechanism including a differential member which is revolved as the speeds of said rotatable members vary when differentials occur between the velocities of said carrier elements, and mechanism adapted to be placed into operation by the 5 rotation of said differential member to effect a change in, and synchronize the velocity of one of said elements with that of said other carrier element irrespective of variations in velocity of said last carrier element.
- 10 7. Means for automatically synchronizing the velocities of two movable carrier elements each having a surface portion in close proximity to the others and moving in the same linear direction, said means including two freely rotatable cylindrical members 15 one of which is disposed so that its periphery frictionally engages each of said carrier elements so as to be rotated through the movement thereof at a peripheral speed 20 corresponding to the velocity of said carrier element, a differential mechanism operatively associated with and driven by said freely rotatable members, said differential mechanism having a differential member 25 adapted to rotate as the speeds of said rotatable members vary when differentials occur between said velocities of said carrier elements, a variable speed mechanism through 30 which one of said carrier elements is driven, and which has a rotatable part which is 35 normally substantially inert, and which, when moved, is adapted to actuate said speed mechanism, and means for moving said part through the rotation of said differential 40 member to effect a variation of velocity of the carrier element driven through said speed mechanism to synchronize the velocities of said carrier elements.
- 45 8. Means for automatically synchronizing the velocities of two movable carrier elements each having a surface portion in close proximity to the other and moving in the same linear direction, said means including two freely rotatable cylindrical members 50 one of which is disposed so that its periphery frictionally engages each of said carrier elements so as to be rotated through the movement thereof at a peripheral speed corresponding to the velocity of said carrier element, a differential mechanism operatively 55 associated with and driven by said rotatable members, said differential mechanism having two members operatively associated with and driven by said freely rotatable members and also having a differential 60 member adapted to rotate as the speeds of said rotatable members vary when differentials occur between said velocities of said carrier elements, a variable speed mechanism through which one of said carrier elements is driven and which has a movable 65 part which is normally substantially inert, and which when moved, is adapted to actuate said variable speed mechanism, and mechanism interposed between said differential mechanism and said variable speed 70 mechanism and which is adapted to be placed into operation by the rotation of said differential member to move said movable part of said speed mechanism to effect a change in the velocity of the carrier element driven through said speed mechanism and synchronize the velocities of said carrier elements.
- 75 9. Means for automatically synchronizing the velocities of two movable carrier elements each having a surface portion in close proximity to the other and moving in the same linear direction, one of said elements having driving means for driving one of said carrier elements at a substantially constant velocity, and said other element having driving means for driving the same at substantially the same velocity as said other carrier element, said means being capable of variations in speed, said automatic synchronizing means comprising two rotatable members one of which operatively engages each of said carrier elements so as to be rotated through the movement thereof and one of said members being freely rotatable and frictionally engaging one of said carrier elements so as to be rotated thereby at a peripheral speed corresponding to the velocity of said carrier element, a differential mechanism operatively 80 associated with and driven by said rotatable members, said differential mechanism having a differential member adapted to move as the speeds of said rotatable members vary when differentials occur in the velocities of said carrier elements, and connections between said differential mechanism and said last mentioned driving means, whereby when fluctuations occur in the velocity of said carrier element driven thereby, such as to cause differential between said rotatable members and consequent movement of said differential member, said last mentioned driving means will be actuated to effect a change in and restore the 85 velocity of said carrier element to that of said other carrier element.
- 90 10. Means for automatically synchronizing the velocities of two movable carrier elements each having a surface portion in close proximity to the other and moving in the same linear direction, one of said carrier elements being driven through a variable speed mechanism, including a belt driven cone pulley and a shifter device for shifting said belt along said pulley, said automatic synchronizing means including two rotatable members at least one of which operatively engages one of said carrier elements so as to be rotated through the move- 95 100 105 110 115 120 125 130

ment thereof at a peripheral speed corresponding to the velocity of said carrier element, a differential mechanism operatively associated with and driven by said rotatable members, said differential mechanism having a differential member adapted to rotate as the speeds of said rotatable members vary when the differentials occur between said relative velocities of said carrier elements, and means disposed between said differential mechanism and said variable speed mechanism for translating said rotary motion of said differential member into a linear movement of said belt shifter device to actuate said variable speed mechanism and synchronize the velocity of the carrier element driven therethrough with that of said other carrier element.

11. Means for automatically synchronizing the velocities of two movable carrier elements, each having a surface portion in close proximity to the other and moving in the same linear direction, one of said carrier elements being driven through a variable speed mechanism, including a belt driven cone pulley and a shifter device for shifting said belt along said pulley, said automatic synchronizing means including two rotatable members at least one of which operatively engages one of said carrier elements so as to be rotated through the movement thereof at a peripheral speed corresponding to the velocity of said carrier element, a differential mechanism operatively associated with and driven by said rotatable members, said differential mechanism having a differential member adapted to rotate as the speeds of said rotatable members vary when differentials occur between said relative velocities of said carrier elements, a ratchet mechanism connected to said shifter device including two opposed ratchets, both of said ratchets being normally substantially inert and having no effect on said shifter device, and either one of which is adapted to be placed into position for actuating said shifter device to shift said belt in one direction or another, and connections between said differential member and said ratchet mechanism for placing either one of said ratchets into operative position to move said shifter device, whereby the rotation of said differential member is utilized to change the velocity of the carrier element driven through said speed mechanism and synchronize it with that of said other carrier element.

12. Means for automatically synchronizing the velocities of two movable carrier elements each having a surface portion in close proximity to the other and moving in the same linear direction, said means including two rotatable members at least one of which operatively engages one of said carrier elements so as to be rotated through

the movement thereof at a peripheral speed corresponding to the velocity of said carrier element, a differential mechanism operatively associated with and driven by said rotatable members, said differential mechanism having a differential member adapted to move as the speeds of said rotatable members vary when differentials occur between said velocities of said carrier elements, whereby the movement of said differential member is utilized to actuate said variable speed mechanism and synchronize the velocity of said carrier element driven therethrough with that of said other element, and an indicating member secured to said rotatable differential member so as to move therewith to indicate, by its direction of rotation, when differential movement occurs, and the character of said movement.

13. Means for automatically synchronizing the velocities of two movable carrier elements each having a surface portion in close proximity to the other and moving in the same linear direction, said means including two freely rotatable members at least one of which is disposed so that its periphery frictionally engages one of said carrier elements so as to be rotated through the movement thereof at a peripheral speed corresponding to the velocity of said carrier element, a differential mechanism operatively associated with and driven by said freely rotatable members, said differential mechanism having a differential member adapted to move as the speeds of said rotatable members vary when differentials occur between said velocities of said carrier elements, whereby the movement of said differential member is utilized to actuate said variable speed mechanism and synchronize the velocity of said carrier element driven therethrough with that of said other carrier element, an indicating member secured to said rotatable differential member so as to move therewith to indicate, by its direction of rotation, when differential occurs, and the character of said movement, and an electric signal device adapted to be actuated by the rotation of said differential member to give warning of the presence of and apprise one of the character of differentials between said relative velocities of said carrier elements.

14. Means for automatically synchronizing the velocities of two movable carrier elements each having a surface portion in close proximity to the other and moving in the same linear direction, one of said carrier elements being driven through a variable speed mechanism including a belt driven cone pulley and a shifter device for shifting said belt along said pulley, said automatic synchronizing means including two rotatable members at least one of which operatively engages one of said carrier elements so as to be rotated through the movement

thereof at a peripheral speed corresponding to the velocity of said carrier element, a differential mechanism operatively associated with and driven by said rotatable members, said differential mechanism having a differential member adapted to rotate as the speeds of said rotatable members vary when differentials occur between said relative velocities of said carrier elements, a ratchet mechanism connected to said shifter device including two opposed ratchets, either of which when turned is adapted to move said shifter device, a dog for each ratchet for engaging and turning its ratchet in a direction opposite to the other ratchet, means for reciprocating said dogs to turn said ratchets, means for normally holding both of said dogs in inoperative relation to said ratchets in such manner that the resulting movement of said ratchets permits said shifter device to remain substantially inert, and means actuated by the rotation of said differential member for engaging one of said dogs with its ratchet to turn said ratchet and move said shifter device, whereby the velocity of the carrier element which is driven through said variable speed mechanism is synchronized with that of said other carrier element.

15. Means for automatically synchronizing the velocities of two movable carrier elements each having a surface portion in close proximity to the other and moving in the same linear direction, one of said carrier elements being driven through a variable speed mechanism including a belt driven cone pulley and a shifter device for shifting said belt along said pulley, said automatic synchronizing means including two rotatable members at least one of which operatively engages one of said carrier elements so as to be rotated through the movement thereof at a peripheral speed corresponding to the velocity of said carrier element, a differential mechanism operatively associated with and driven by said rotatable members, said differential mechanism having a differential member adapted to rotate as the speeds of said rotatable members vary when differentials occur between said relative velocities of said carrier elements, a ratchet mechanism connected to said shifter device including a pair of opposed ratchets fixed to said feed screw, a dog for each ratchet for engaging and turning its ratchet in a direction opposite to the other ratchet, means for normally holding both of said dogs in their inoperative relation to said ratchets to permit said shifter device to remain substantially inert, and rocker mechanism adapted to be actuated by the rotation of said differential member for engaging one of said dogs with its ratchet to permit it to turn its ratchet and move said shifter device, whereby the velocity of the carrier element which is driven through said variable speed mechanism is synchronized with that of said other carrier element.

20. Means for automatically synchronizing the velocities of two rotatable members as the speeds of said rotatable members vary when differentials occur between said relative velocities of said carrier elements, a ratchet mechanism connected to said shifter device including two opposed ratchets either of which when turned is adapted to move said shifter device, a dog for each ratchet for engaging and turning its ratchet in a direction opposite to the other ratchet, an eccentric adapted to be rotated through said variable speed mechanism to reciprocate said dogs and turn said ratchets, means for normally holding both of said dogs in inoperative relation to said ratchets to permit said shifter device to remain substantially inert, and means actuated by the rotation

of said differential member for engaging one of said dogs with its ratchet to permit it to turn its ratchet and move said shifter device, whereby the velocity of the carrier element which is driven through said variable speed mechanism is synchronized with that of said other carrier element.

16. Means for automatically synchronizing the velocities of two movable carrier elements each having a surface portion in close proximity to the other and moving in the same linear direction, one of said carrier elements being driven through a variable speed mechanism including a belt driven cone pulley and a shifter device including a feed screw, and a member movable lengthwise thereof and engaging said belt for shifting the same along said pulley and which is moved by turning said screw, said automatic synchronizing means including two rotatable members at least one of which operatively engages one of said carrier elements so as to be rotated through the movement thereof at a peripheral speed corresponding to the velocity of said carrier element, a differential mechanism operatively associated with and driven by said rotatable members, said differential mechanism having a differential member adapted to rotate as the speeds of said rotatable members vary when differentials occur between said relative velocities of said carrier elements, a ratchet mechanism connected to said shifter device including a pair of opposed ratchets fixed to said feed screw, a dog for each ratchet for engaging and turning its ratchet in a direction opposite to the other ratchet, means for normally holding both of said dogs in their inoperative relation to said ratchets to permit said shifter device to remain substantially inert, and rocker mechanism adapted to be actuated by the rotation of said differential member for engaging one of said dogs with its ratchet to permit it to turn its ratchet and move said shifter device, whereby the velocity of the carrier element which is driven through said variable speed mechanism is synchronized with that of said other carrier element.

17. Means for automatically synchronizing the velocities of two travelling carrier elements, said means including two freely rotatable members at least one of which is disposed in operative relation to one of said carrier elements so that said carrier elements frictionally engage and pass over the peripheries of said members, whereby each member is rotated at a peripheral speed corresponding to the velocity of the respective carrier elements, a differential mechanism operatively associated with and driven by said rotatable members, said mechanism having a differential member which moves as the speeds of said rotatable members vary when differentials occur between the

velocities of said carrier elements, and means actuated by said differential member to automatically change the velocity of one of said carrier elements and synchronize the same with that of the other carrier element.

18. Means for automatically synchronizing the velocities of two travelling carrier elements, one of which is driven through a variable speed mechanism, said synchronizing means including two freely rotatable members at least one of which is disposed in operative relation to one of said carrier elements so that said carrier elements frictionally engage and pass over the peripheries of said members, whereby each member is rotated at a peripheral speed corresponding to

the velocity of the respective carrier elements, a differential mechanism operatively associated with and driven by said rotatable members, said mechanism having a differential member which moves as the speeds of said rotatable members vary when differentials occur between the velocities of said carrier elements, and means actuated by said differential member to actuate said variable speed mechanism to automatically effect a change in the velocity of the carrier element driven therethrough and synchronize it with that of said other carrier element.
